UNITED STATES PATENT OFFICE.

OTTO KRETER AND GEORGE E. KRETER, OF SAN ANTONIO, TEXAS.

OPERATING MECHANISM FOR FLUSHING DEVICES.

1,051,123.

Specification of Letters Patent.

Patented Jan. 21, 1913.

Application filed January 24, 1912. Serial No. 673,039.

To all whom it may concern:

Be it known that we, OTTO KRETER and GEORGE E. KRETER, citizens of the United States, and both residents of San Antonio, in the county of Bexar and State of Texas, have invented a new and Improved Operating Mechanism for Flushing Devices, of which the following is a full, clear, and exact description.

10 This invention relates to operating mechanism for flushing devices used with water closets and the like, and has reference more particularly to the combination of an actuating member adapted to be operatively associated with a flushing device, an operating member tending to maintain a normal position and adapted to be actuated by a closet seat, and a dog operable by said last-mentioned member and adapted to engage 20 said actuating member during a predetermined part of its movement.

The object of the invention is to provide a simple and efficient operating mechanism for flushing tanks, valves or other flushing devices used with water closets and the like, which can be readily applied to different types of water closets without necessitating alteration in their construction or arrangement, which is compact in form and thus 25 takes up little room, which renders possible the automatic operation of the flushing device with which the water closet is provided, which obviates the necessity of manual operation of the flushing device, but which permits the same should it be desirable.

The invention consists in the construction and combination of parts to be more fully described hereinafter and particularly set forth in the claim.

40 Reference is to be had to the accompanying drawings forming a part of this specification, in which similar characters of reference indicate corresponding parts in all the views, and in which—

45 Figure 1 is a perspective view of a water closet, showing an embodiment of our invention applied thereto; Fig. 2 is an enlarged front elevation of the operating mechanism; and Fig. 3 is an enlarged longitudinal section of the device.

Before proceeding to a more detailed explanation of our invention, it should be clearly understood that while we have shown the mechanism applied to a water closet provided with the usual flushing tank, the mechanism can also be advantageously em-

ployed for operating other types of flushing devices, for example, flushing valves. To adapt the mechanism for such further use, only such changes would be necessary as fall within the province of any skilled mechanic to design. Certain of the details of construction shown for example herewith, form no part of the invention and can be varied in accordance with individual preference and special conditions, without deviating from the spirit of the invention as defined in the appended claim.

Referring more particularly to the drawings, we have shown for example, a water closet 10 of the conventional construction, having associated therewith the usual removable lid 11 and a cover 12. A flushing tank 13 is arranged above the closet, and communicates therewith by means of a pipe 14. The flushing tank, the mechanism of which is not shown, is of any suitable construction and has an operating arm or lever 15 to which is attached a depending chain 16 which permits the manual operation of the tank. The seat 11 of the closet is hinged at the rear edge and can be raised and lowered.

Positioned adjacent to the closet is a suitable base 17 having mounted thereon a cylindrical casing 18 provided at the lower end with a laterally extended flanged collar 19 permitting the attachment of the frame to the base by means of screws 20 or the like. At the upper end the casing has a head 21 screwed into position thereupon and provided with an opening 22 through which the chain 16 passes. Movably mounted within the casing is an actuating member 23 consisting of a bar having at one edge a plurality of teeth 24 and slidably mounted between guide lugs 25. Within the casing, underneath the actuating member, is an inwardly extending projection 26 constituting a stop to limit the downward movement of the actuating member.

A standard or pivot support 27 having at the lower end a flanged collar 28, is mounted by means of the latter, upon the base, the collar being secured in position by means of screws 29 or the like. The upper end 30 of the standard is bifurcated and has mounted between the sides thereof an operating lever arm 31 movably held in place by means of a pivot pin or rivet 32. The end 33 of the lever arm remote from the casing 18 is upwardly disposed and carries at

the extremity a laterally extending roller 34 mounted upon a spindle 35. The arrangement is such that the roller engages under the edge of the closet seat at the side of the same, so that when a weight is imposed upon the seat the latter will serve to depress the operating lever. The end of the lever extends into the casing 18 through a slot 36 in the wall thereof. A spring 37 located 10 within the casing is secured to the entering end of the lever and to a lug 38 of the casing, and tends to hold the lever in a normally depressed position such that the outer end of the lever is raised and the seat is correspondingly raised a slight distance as is shown in Fig. 1.

The end 39 of the lever within the casing is bifurcated, and has mounted between the sides thereof a dog 40 movably held in place 20 by means of a pivot pin or rivet 41. The dog has at the lower end a tapered part 42 adapted to engage the teeth 24 as will be pointed out more clearly hereinafter. The upper end 43 of the lever is so formed that it constitutes a counterbalance and tends to swing the lever into position such that the end 42 thereof engages the teeth of the actuating member. Within the casing, above the dog, is a lug or projection 44 constituting 30 a stop adapted to be engaged by the dog to limit the upward movement of the lever. The casing furthermore, has therein a rounded, offset strip 45 secured thereto in any suitable manner and constituting a release, being adapted to be engaged by the dog during the movement of the latter, and to displace it from engagement with the actuating member.

The operation of the mechanism is as follows: The spring 37 tends to maintain the parts in normal positions such that the outer end of the operating lever arm is raised and the seat is correspondingly raised. When a weight is imposed upon the seat the lever is depressed against the tension of the spring. The dog rides upwardly with the lever and passes beyond the release 45 so that the counterweighted end of the dog brings it into operative relation with the actuating member 23. When the weight is removed 50 from the seat the spring 37 at once pulls the lever downwardly and owing to the engagement of the dog with the actuating member,

the latter is also moved downwardly and the flushing device is thereby actuated 55 through the connecting chain 16. As the dog moves downwardly with the lever it rides over the release and is thereby displaced from engagement with the actuating member. Accordingly, the actuating member and the chain can move upwardly during the course of the automatic operation of the flushing device. It will be readily seen that the mechanism is so constructed that it will not hinder the manual operation of the 60 flushing device, should such operation be desirable. The seat can be raised without affecting the mechanism or the coöperation of the same with the flushing device.

Having thus described our invention, we 70 claim as new, and desire to secure by Letters Patent:

In combination, a casing, an actuating member slidably mounted within said casing and movable longitudinally thereof, said casing having therein guides for said member and a stop for limiting the movement of said member, said actuating member being adapted to be operatively associated with a flushing device and having teeth, a movable 75 operating lever having one end extending into said casing, a spring within said casing and secured thereto and to said operating member and tending to hold said operating member in a normal position, said operating member having means whereby it can be actuated by a closet seat, a dog pivotally carried by said operating member within said casing and having a counterweight whereby it tends to maintain an operative 80 relation with respect to said operating member, a fixed release within said casing and adapted to engage said dog, to release the same from said actuating member when said operating member assumes a predetermined 85 position, and a stop within said casing, for limiting the movement of said operating member.

In testimony whereof we have signed our names to this specification in the presence of 100 two subscribing witnesses.

OTTO KRETER.
GEORGE E. KRETER.
